US00D971209S

(12) **United States Design Patent** (10) **Patent No.:** **US D971,209 S**
(45) **Date of Patent:** ** *Nov. 29, 2022

(54) **DISPLAY DEVICE**

(71) Applicant: **Google LLC**, Mountain View, CA (US)

(72) Inventors: **Matthew Seflic**, San Jose, CA (US);
Maj Isabelle Olsson, Sunnyvale, CA (US); **Carl Cepress**, Mountain View, CA (US); **Katherine Morgenroth**, San Mateo, CA (US)

(73) Assignee: **GOOGLE LLC**, Mountain View, CA (US)

(*) Notice: This patent is subject to a terminal disclaimer.

(**) Term: **15 Years**

(21) Appl. No.: **29/807,347**

(22) Filed: **Sep. 10, 2021**

Related U.S. Application Data

(63) Continuation of application No. 29/663,749, filed on Sep. 18, 2018, now Pat. No. Des. 936,651.

(57) **CLAIM**

The ornamental design for a display device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a display device showing our design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

1 Claim, 4 Drawing Sheets
(4 of 4 Drawing Sheet(s) Filed in Color)
